UNITED STATES PATENT OFFICE.

CHARLES H. COLLINS, OF COLONIE, NEW YORK.

LOOM FOR WEAVING PILE FABRIC.

Application filed November 16, 1925. Serial No. 69,226.

My invention relates to looms for weaving single pile fabrics, and the object of my invention is to construct a loom which will produce, directly and mechanically, 5 new and improved pile fabrics having the general appearance of a chenille goods made in accordance with the present art wherein certain preliminary weaving, and some hand operations are required. A further object 10 is to construct a loom which will make possible the production, at a comparatively low cost, of any of the fabrics disclosed in the joint application of James T. Garvin and myself for Letters Patent for improvements 15 in pile fabrics, Serial No. 67,773, filed November 9th, 1925.

In the accomplishment of my purposes I may utilize any suitable present type of single pile fabric loom, adapting it to my 20 particular requirements by making certain changes therein and additions thereto. The additions which are to be made to one present type loom are illustrated in the accompanying drawings, in which:

25 Fig. 1 is a plan view of the additions which are to be made in a present type "four to one" loom, portions of which are shown.

Fig. 2 is a side elevation of Fig. 1, picking post and pile and stuffer cams omitted.

30 Fig. 3 is a plan of the face and stuffer cam,

Fig. 4 is a plan of the wire motion cam, and

Fig. 5 is a plan of the binder work cams, 35 all as used on my improved pile fabric loom when arranged for weaving a fabric wherein four picks of the weft yarn are to be laid between changes in the binder warp shed.

40 Fig. 6 is a sketch illustrating one full weaving cycle, and Fig. 7 is a sketch illustrating the manner in which the selvage warps are caused to anchor the loops formed in the weft yarn.

The same reference characters refer to the 45 same parts throughout the several views, all of which are in a sense illustrative or diagrammatic only.

Referring to the drawings, A² and A³ indicate portions of the side frames of a 50 usual pile fabric loom, and A⁴ a portion of the usual driven crank shaft.

C² is the main cam shaft in my improved loom, and on it are secured the usual pair 55 of picking post cams a cam C⁵ adapted to raise and lower the usual heddle frames which carry the pile and stuffer warps, a

wire motion cam C⁶ adapted to actuate the mechanism which withdraws and inserts the usual pile wires, and a wire-carrying-over cam. In the improved loom as illustrated, 60 the main cam shaft C² is to be driven from the crank shaft A⁴ in a manner which will cause it to make one-quarter of a revolution with each revolution of the shaft, these means being here shown as a pinion A⁵, 65 meshing with and driving the spur gear C⁹.

Journalled on the main cam shaft C² (or any other suitable point), are the binder warp cams C⁸, which are supported by a sleeve of the gear C¹⁰ and are driven from the crank shaft A⁴, in a manner which will cause them to make one-eighth of a revolution 70 with each revolution of the crank shaft A⁴, the means here illustrated being a pinion A⁶, secured on the crank shaft and meshing 75 with and driving the spur gear C¹⁰, which is idly supported, preferably on the shaft C², and so secured or connected to or with the cams C⁸, that said cams and spur gear will rotate as a unit. The cams C⁸ are identically 80 shaped, but are so incorporated in the unit that they actuate the usual binder warp heddles in opposite directions.

If the loom is to be adapted to make one 85 of the modified fabrics disclosed in the joint application by Garvin and myself above referred to, the binder warp cam unit is to be so geared that it will make but that part of a revolution which will be equal to a speed of—

one

the number of picks of weft yarn which is to 90 be placed between changes in the binder warp shed

95—that of the crank shaft; i.e., the ratio will be "one to ten," "one to eight" or "one to six," depending on the style weave which it is desired to produce.

100 Mounted parallel with main cam shaft C², is an auxiliary cam shaft D², driven from some moving part of the loom in a manner which will cause it to make one-half of one revolution with each revolution of the crank shaft A⁴, the means being 105 here illustrated as a chain drive D³, direct from the crank shaft. On this auxiliary cam shaft D², is secured a pair of selvage cams D⁴ and D⁵, each of which engages with one arm of one of a pair of double 110 armed levers D⁶, which are fulcrumed at D⁷, and the other arm of which controls

the position of a selvage post or heddle D⁸. While I have illustrated these levers as being actuated in one direction by means of a spring D⁹, it is obvious that by using a box type of cam these springs could be dispensed with.

The selvage cams D⁴ and D⁵ are to be identically shaped, each having but one high point, and the pair are to be so set 10 upon the shaft D² that the high point of one will work 180 degrees in advance of, or stand diametrically opposite the high point of the other.

The binder warp cams C⁸, journalled on 15 the shaft C², are also to have but one high point, and to be so mounted in constructing the unit of which they form a part, that the high point of one will stand diametrically opposite the high point of the 20 other; they being adapted to actuate or cause the movement of the heddle frames in reverse directions.

As above set forth, the binder warp cams, and the gear C¹⁰ which is a part of that 25 unit, makes but one revolution to each two revolutions of the auxiliary cam shaft D², and the cams thereon, each four revolutions of the main cam shaft C², and each eight revolutions of the driven crank shaft A⁴, 30 when the loom is adapted to make the preferred form of fabric illustrated in the joint application before referred to.

To adapt the loom to make the two modifications of the fabric which are mentioned 35 therein, it is necessary to make the relative sizes of the gears such that the relative speed of the binder warp cam unit, and the main cam shaft, to that of the driven crank shaft will be such as to give the proper 40 number of picks between changes in the binder warp sheds; and to so change the shape of the cams that the relative length of the high and low portions thereof are such as will give the proper dwell at the 45 two extremes.

When the loom is arranged as illustrated and described, eight picks of weft yarn are placed during each full cycle of operation, the cams so set and proportioned 50 that four of the picks are placed in the intervals between change in the binder warp shed, or reversal of the relative positions of the binder warp heddle frames. (When the loom is arranged to make the modified 55 fabric illustrated in the before mentioned joint application, ten picks would necessarily be placed during a full cycle, five being placed in the intervals between changes in the binder warp shed; and if 60 arranged to make the further modification mentioned in said joint application, but six picks would be placed during a full cycle, three being placed between changes in the binder warp shed.)

65 In the loom here illustrated the first pick

is placed with the pile and stuffer warps down, these warps being raised between the placing of the first and second picks, and held raised during the placing of the second and third picks, which when beat up 70 will be in the lower weft plane of the fabric, as also will be the sixth and seventh picks; the first, fourth, fifth, and eighth picks forming the upper weft plane. A pile wire is inserted during the times the pile and stuffer warps are in the raised position. Between the placing of the third and fourth picks the pile and stuffer warps are lowered, the binder warp shed reversing between the fourth and fifth picks. After the fifth 80 pick is placed the pile and stuffer warps are again raised and held raised until after the sixth and seventh picks are placed, and a pile wire inserted; they are then lowered and the eighth pick placed, and the binder warp shed again reversed and the cycle of operation is completed.

The selvage heddle cams are so set that when the weft yarn reverses direction the loop formed therein will lie across, or be 90 around the selvage warp on the edge of the fabric where the loop is formed, and the placed pick of weft yarn is thereby prevented from being drawn back into the shed when the reverse pick is made. For 95 safety the selvage warp may be a plural number of yarns manipulated as one.

Because of the comparative ease with which the selvage warps may be crossed in the manner illustrated, I prefer to change 100 their relative positions after each pick is laid, whether it be laid in the upper or lower weft plane, thereby anchoring each loop formed in the weft yarn at the edge 105 of the fabric where formed. It is of course obvious that the crossing of the selvage warps is not necessary at the points where the normal crossing of other warps would act as an anchor for the loops in the weft 110 yarn. It is, however, necessary that the loops between successive picks of weft yarn laid in the same shed and in the lower weft plane must be anchored, a selvage warp in order to insure its not being drawn back 115 into the shed, and beyond the edge of the fabric when the succeeding pick is made.

In my improved loom the pile wires are inserted during the time the pile and stuffer warp heddle frames are in the raised position, and as but one wire is withdrawn and inserted during each half cycle, or during each four revolutions of the crank shaft, it is obvious that a quick insertion and a slow withdrawal of the pile wire is entirely feasible. This makes available substantially, 120 three quarters of the cam circumference which may be used to cause the withdrawal of the pile wire, thus making available ample power which may be utilized to handle 125 an extra high pile wire, as the withdrawal 130

of such wires at a slow speed will not cause them to become overheated to the extent which they would be were it necessary to withdraw them at the same speed at 5 which they are inserted.

I claim:

1. In a single pile multiplane fabric loom, in combination with the usual driven crank shaft: a main cam shaft having secured 10 thereon a pair of picker cams, a wire-carrying-over cam, a wire motion cam adapted to withdraw a wire at a comparatively low speed and insert it at a comparatively high speed, during each revolution of the main 15 cam shaft, and a pile and stuffer cam having but one high point and adapted to cause the pile and stuffer warps to be raised immediately after the first pick is inserted in shed of binder warp, and held raised until immediately before the last of a series of picks 20 of weft yarn is placed in the binder warp shed between changes therein; means for causing rotation of said cam shaft at a speed of—

25 one

number of picks of weft yarn placed in the binder warp shed between changes therein

that of said driven crank shaft; a rotatable 30 binder-warp-cam unit journalled on said main cam shaft and adapted to change the binder warp shed twice during each revolution of said unit; means for causing rotation of said unit at one-half the speed of 35 said main cam shaft; an auxiliary cam shaft, with a pair of selvage heddle cams thereon adapted to actuate selvage heddles whereby one or the other of the selvage warps controlled thereby will be caused to lie inside 40 of the loops formed in the weft yarn due to reversal in the direction thereof, and prevent said loops being drawn inward beyond the edge of the fabric; and means for causing rotation of said auxiliary cam shaft.

45 2. In a single pile multiplane fabric loom, in combination with the usual driven crank shaft: a main cam shaft having secured thereon a pair of picker cams, a wire-carrying-over cam, a wire motion cam, and 50 a pile and stuffer cam having but one high point and adapted to cause the pile and stuffer warps to be raised immediately after the first, and held raised until immediately before the last of a series of picks of weft 55 yarn is placed in the binder warp shed between changes therein; means for causing rotation of said cam shaft at a speed of—

one

60 number of picks of weft yarn placed in the binder warp shed between changes therein

that of said driven crank shaft; a rotatable binder-warp-cam unit journalled on said main cam shaft and adapted to change the binder warp shed twice during each revolution 65

of said unit; means for causing rotation of said unit at one-half the speed of said main cam shaft; an auxiliary cam shaft, with a selvage heddle cam thereon adapted to actuate a selvage heddle whereby 70 a selvage warp controlled thereby will be caused to lie inside of the loops formed in the weft yarn due to the reversal in the direction thereof, and prevent said loops being drawn inward beyond the edge of the 75 fabric; and means for causing rotation of said auxiliary cam shaft.

3. In a single pile multiplane fabric loom, in combination with the usual driven crank shaft: a main cam shaft having secured 80 thereon the picker and wire carrying over cams, and a pile and stuffer cam having but one high point and adapted to cause the pile and stuffer warps to be raised immediately 85 after the first of a series of picks of weft yarn, and held raised until immediately before the last of the series of picks of weft yarn is placed in the binder warp shed between changes therein; means for actuating the wire motion mechanism; means for causing rotation of said cam shaft at a speed of—

90 one

number of picks of weft yarn placed in the binder warp shed between changes therein

that of said driven crank shaft; a rotatable binder-warp-cam unit adapted to change the binder warp shed twice during each revolution of said unit; means for causing rotation of said unit at one half the speed of 95 said main cam shaft; and means whereby a selvage warp is caused to lie inside of, and so prevent loops formed in the weft yarn by the reversal in the direction thereof, from being drawn inward beyond the edge of the fabric.

4. In a single pile multiplane fabric loom, in combination with the usual crank shaft, picker mechanism, and wire-carrying-over 100 and wire motion mechanisms: means for actuating said mechanisms once during each revolution of the main cam shaft; a main cam shaft, with a pile and stuffer cam thereon adapted to cause the pile and stuffer warps 115 to be raised and held up during the time a plurality of consecutive picks of weft yarn are placed in the same shed and in the lower weft plane; means for causing rotation of said main cam shaft at a speed equal to—

120 one

number of picks of weft yarn placed in the binder warp shed between changes therein

that of the crank shaft; a rotatable binder-warp-cam unit adapted to cause the binder warp shed to be changed twice during each revolution of said unit; means for causing rotation of said unit at one-half the speed 125 of said main cam shaft; and cams adapted to 130

actuate selvage heddles whereby one or the other of a pair of selvage warps is caused to lie inside of loops formed in the weft yarn by reason of the reversal in the direction of said yarn, thereby preventing said loops being drawn inward beyond the edge of the fabric.

5. The method of making a single pile multiplane fabric comprising pile, stuffer, 10 and binder warps, and selvage threads, and consisting of forming a multiplane shed of the warps, inserting a weft shot or shots in

the upper plane, and further inserting a plurality of weft shots in the lower plane of said shed, forming weft loops, anchoring 15 said loops, and thereafter inserting a weft or wefts in the upper plane of said shed, of beating up each weft successively, then crossing the binder warps and successively repeating the above cycle.

20 In testimony whereof I have affixed my signature.

CHARLES H. COLLINS.
